FIG. 1.

FIG. 2.

Inventor

Joseph Singer

By his Attorneys

Edgar State Co.

UNITED STATES PATENT OFFICE.

JOSEPH SINGER, OF NEW YORK, N. Y., ASSIGNOR OF ONE-THIRD TO FREDERIC E. NEVIN
AND ONE-THIRD TO LUDWIG STEINBERG, BOTH OF NEW YORK, N. Y.

DESIGN FOR A BADGE OR BADGE-BUTTON.

51,083.

Specification for Design.

Patented July 24, 1917.

Application filed April 13, 1917. Serial No. 161,915. Term of patent 7 years.

To all whom it may concern:

Be it known that I, JOSEPH SINGER, a citizen of the United States, and residing in New York, in the county and State of New York, have invented a new, original, and ornamental Design for a Badge or Badge-Button, of which the following is a specification, reference being had to the accompanying drawing, forming part thereof.

Figure 1 is an enlarged face view of my newly designed badge or badge button; and,

Fig. 2 an edge view thereof.

I claim:

The ornamental design for a badge or badge button as shown.

JOSEPH SINGER.

Witnesses:

C. E. MULREANY,
H. E. THOMPSON.
